UNITED STATES PATENT OFFICE.

EDWARD WEHNER, OF ANN ARBOR, MICHIGAN, ASSIGNOR OF ONE-HALF TO ELBERT V. CHILSON, OF ANN ARBOR, MICHIGAN.

WORK-HOLDER.

1,234,837.

Specification of Letters Patent.

Patented July 31, 1917.

Application filed November 18, 1916. Serial No. 132,115.

To all whom it may concern:

Be it known that I, EDWARD WEHNER, a citizen of the United States, residing at Ann Arbor, in the county of Washtenaw and 5 State of Michigan, have invented a new and useful Work-Holder, of which the following is a specification.

The device forming the subject matter of 10 this application is a work holder, adapted to retain rungs, spindles, spokes and the like while the same are being rounded or tenoned on the end, by a chuck driven or rotated in a machine, in any suitable manner.

The invention aims to provide novel 15 means whereby the article which is to be rounded or tenoned on the end, is held in place during the rounding or tenoning operation.

Another object of the invention is to provide 20 a swinging frame which, holding the spoke or other object, swings forward to permit the article to enter the chuck head.

The invention aims to provide novel 25 means for returning the frame to its initial or original position.

It is within the province of the disclosure to improve generally and to enhance the utility of, devices of that type to which the present invention appertains.

30 With the above and other objects in view which will appear as the description proceeds, the invention resides in the combination and arrangement of parts and in the details of construction hereinafter described 35 and claimed, it being understood that changes in the precise embodiment of the invention herein disclosed can be made within the scope of what is claimed, without departing from the spirit of the invention.

40 In the accompanying drawings:—

Figure 1 shows in side elevation, a work holder embodying the present invention;

Fig. 2 is a top plan of the work holder, parts being broken away in Figs. 1 and 2;

45 Fig. 3 is an end elevation of the work holder;

Fig. 4 is a vertical section of the work holder, on the line 4—4 of Fig. 3, parts appearing in elevation; and

50 Fig. 5 is a horizontal section on the line 5—5 of Fig. 4.

The device forming the subject matter of this application includes a support 1 carrying a table 2, one end of which, denoted by 55 the numeral 3, projects beyond the sup-

port 1. The end 3 of the table 2 is provided with stops 4 at its sides. The numeral 5 denotes a U-shaped frame held by one or more securing elements 6 to the table 1. The arms of the U-shaped frame 5 are supplied 60 with openings 7 through which passes a bolt 8 carrying a rotatable sleeve 9 located between the arms of the frame 5.

The numeral 10 denotes an inverted U-shaped frame which straddles a bracket 12 65 projecting forwardly from the support 1 near to the lower end of the support. The bracket 12 has notches 11 in its sides, in which the arms 10 of the U-shaped frame 10 are received for vertical adjustment, but 70 against tilting movement. The bracket 12 is held to the support 1 by means of one or more securing elements 14. Mounted in the top of the U-shaped frame 10 are rods 15, carrying nuts 16 which engage the upper 75 and lower faces, respectively, of the top of the frame 10. The upper ends of the rods 15 pass through a bar 17 held against a lug 18 on the bottom of the end 3 of the table 2, by a bolt 19 or the like. There are heads 20 80 on the upper ends of the rods 15, the heads 20 being bound between the lower face of the lug 18 and the bar 17. The rods 15, therefore, cannot move upwardly, but by adjusting the nuts 16 on the rods, the U- 85 shaped frame 10 may be raised and lowered, the said frame sliding in the notches 11 of the bracket 12.

A pivot element, preferably in the form of a rod 21, passes through the lower ends 90 of the U-shaped frame 10, below the bracket 12. On the ends of the rod 21 are pivoted the depending arms of an inverted U-shaped frame 22. The frame 22 may be swung rearwardly, against the action of a spring 95 23 attached to the forward face of the support 1 and bearing on one arm of the frame. The arms of the frame 22 engage with the stops 4 on the edges of the end 3 of the table 2, under the action of the spring 23.

100 Superposed on the upper end of the frame 22 is a rectangular, relatively fixed jaw 24, in the base arm of which is formed an elongated slot 25. A bolt or like clamping element 26 passes through the slot 25 and is 105 engaged with the top of the frame 22. Upon its inner edge, the upright arm of the rectangular jaw 24 is equipped with teeth 27.

110 Mounted on that arm of the frame 22 which is remote from the fixed jaw 24 is a

bracket 28 carrying a pivot element 29 on which is mounted to swing a movable jaw 30, overhanging the top of the frame 22. The jaw 30 is provided at its inner end, and 5 at its top and bottom, with elongated fingers 31 and between the fingers 31, the end of the jaw 30 is supplied with teeth 32. A spring 33 is penetrated by the bolt 26 which holds the movable jaw 24 in place, and is bound between the base of the jaw 24 and the top of the frame 32, as Fig. 3 will make evident. 10 The free end of the spring 33 engages beneath the jaw 30 and tends to lift the jaw. In practical operation, the article which 15 is to be rounded or tenoned, is placed between the movable jaw 30 and the upright arm of the fixed jaw 24, the work being pushed down so that it is bound against the teeth 27 of the fixed jaw, and is engaged by 20 the teeth 32 of the movable jaw 30, between the fingers 31. The article passes beneath the sleeve 9. By swinging the frame 22 from the solid line position of Fig. 4 to the dotted line position, the work may be advanced so that it will coöperate properly 25 with the chuck. The spring 23 serves to return the frame 22 to the solid line position of Fig. 4, after the tenoning operation has been carried out.

30 The roller 9 may be shifted vertically in the holes 7 of the frame 5, so that the article which is being tenoned will be positioned properly with respect to the tool whereby the end of the spoke or rung is rounded.

35 As hereinbefore stated, it is possible to

shift the U-shaped frame 10 vertically, and consequently the frame 22 and the jaws 30 and 24, by manipulating the nuts 16 on the rods 15.

Having thus described the invention, what 40 is claimed is:—

1. In a device of the class described, a supporting structure; a guiding means superposed on the supporting structure; a frame mounted on the supporting structure 45 for raising and lowering; means for raising and lowering the said frame; a second frame pivoted to the first specified frame; spring means for advancing the last specified frame; a stop on the supporting structure 50 and limiting the advancing movement of said frame under the action of the spring; a relatively fixed jaw on the second specified frame; and a movable jaw on the said frame and coacting with the fixed jaw. 55

2. In a device of the class described, a supporting structure; a guiding means thereon; a frame mounted to swing with respect to the supporting structure, toward and away from the guiding means; coacting jaws carried by the frame; and means for raising and lowering said frame. 60

In testimony that I claim the foregoing as my own, I have hereto affixed my signature in the presence of two witnesses.

EDWARD WEHNER.
